WINDOW ASSEMBLY

Sam H. Vuncannon, Coral Gables, Fla., assignor to Vun-Russ Company, Inc., Hialeah, Fla., a corporation of New York

Application June 16, 1955, Serial No. 515,881

15 Claims. (Cl. 20—42)

The present invention relates to new and useful improvements in windows and more particularly to novel awning type window assembly units constructed primarily from extruded elements and assembled in a manner to permit ready removal of the tilttable vents and omission of the customary transversely extending vent division framing elements.

In recent years, the use of awning type metal window assembly units has grown to tremendous volumes. This is particularly true in home and apartment house usage where the awning type or horizontally hinged window vents have become popular because of the ability to vent the window opening even in inclement weather without any appreciable danger of the rain entering through the vented opening in the absence of a driving wind. Windows of this type proposed in the prior art customarily employ vent framing elements extending transversely between the jambs to provide intermediate sealing members and structural reinforcement. These prior art window assemblies also have customarily been furnished with non-removable tilttable vents necessitating original installation with the vents unglazed since the contractor normally is required to install the assembly units in place to define the wall opening and then build the remainder of the wall and building around them and is not willing to assume the risk and danger of breakage of the window glass. The result is that the unglazed vent framing and the transverse framing elements of the prior art window assemblies present inviting supports for scaffolding and walk boards and are used as ladder steps and are often damaged by such misuse. Also the vents themselves must be glazed after completion of the heavy construction by glaziers working either from ladders or from expensive outside scaffolding with their incident hazards to the workers.

Furthermore, the window units of the prior art, due to the transverse framing elements and their hinge constructions, have been limited in their angle of opening so that full advantage of the descending cool air, often present in warm and hot weather after the sun has set, cannot be effectively directed into the interior of the house or apartment building to more effectively cool the occupants. This limitation together with the non-removability of the prior art window vents also poses a cleaning problem since the exterior of the glass pane cannot be effectively and conveniently washed except by standing on ladders or other support surfaces provided exteriorly of the building.

It, accordingly, is the primary object of this invention to provide a window frame assembly unit avoiding the aforesaid objections of the prior art window units which, due to the form and manner of production of its various elements, effects substantial savings in manufacture and installation.

Another important object of the present invention resides in the provision of an awning type window assembly unit having a rigid rectangular frame made up solely of

2

interconnected jamb, header and sill members and readily insertable and removable vents adapted for installation after the framing has been mounted in the wall opening whereby glazing may be completed at the factory or in a safe shop and removal may be readily effected to clean the exterior of the vent glass.

Still another important object of the present invention is to provide an awning type window assembly unit having the main framing elements and other structural parts formed principally from lengths of extruded shapes which may be made from aluminum or other suitable metals or materials, even plastic, and glazed vents unitarily mountable and removable from said main framing after the main framing has been secured in the wall opening and completion of the other building construction work likely to cause breakage of the glass panes.

Still another object of the present invention resides in providing an awning type window with pivots offset toward the exterior face of the window main frame but within the confines of the main framing to provide a full 90° or better angle of opening when desired to take advantage of the descending cool air masses prevalent after sundown in warm weather.

A further object of the present invention is to form the main rectangular framing elements of a window unit of a novel cross-sectional configuration, namely, a channel-like element having an inner short wall section and an opposed outer long wall section extending respectively from the opposite edges of the connecting web section and provided adjacent their respective opposite ends with opposed, longitudinally extending rib elements defining socket grooves along the opposed wall sections for respectively receiving inner and outer corner connectors and guide brackets for supporting conventional slide bars and housing suitable frame concealed window operating mechanism.

Still another important object of the present invention is to provide an awning window structure wherein the ventilators are individually removably secured to the frame or operating mechanism for the ventilators, whereby the ventilators may be field mounted to facilitate shop glazing of the ventilators.

A further object of the present invention is to provide an awning window structure wherein the mounting means for the ventilators is adjustable to permit individual movement of a selected end of any ventilator to assure sealing contact with the adjacent frame element of the window structure although the frame may not be installed plumb and level.

Another object of the present invention is to provide an awning window structure with a novel and improved geared operator which is extremely small and compact in structure and so designed as to be concealed and housed within one of the extruded jamb members of the main window frame.

A further object of the present invention is to provide an awning window including one or more ventilators which may be raised above the horizontal to facilitate increased ventilation and readily removed for ease of cleaning the ventilators.

Still another object of the present invention resides in the provision of ventilator units made up of opposed end and top and bottom extrusion bars of double channel form having opposed longitudinally extending rib elements defining socket grooves along one set of the opposed wall sections for receiving corner connectors.

A still further object of the present invention is to provide an awning window that is extremely neat and attractive in appearance, efficient and durable in operation, inexpensive to manufacture and service, and otherwise well adapted for the purposes for which the same is intended.

Further objects will appear from the following description and appended claims when read in conjunction with the attached drawings wherein:

Figure 1 is a schematic perspective view of a window assembly unit made pursuant to the present invention, viewed from an exterior corner thereof and showing the ventilators in partially open position;

Figure 2 is an enlarged fragmentary view of a portion of Figure 1 schematically illustrating the various cross-sections of the ventilators and the header and sill;

Figure 3 is a side elevational view of the window assembly unit of Figure 1 showing the ventilators raised to a horizontal position;

Figure 3A is an enlarged fragmentary view of one corner of the window frame with parts broken away and sectioned to illustrate the preferable means for interconnecting the frame sections;

Figure 4 is an enlarged fragmentary side elevational view with certain parts broken away to better illustrate the ventilator hinge structure of the present invention;

Figure 5 is an enlarged detail of a portion of Figure 4 with certain parts broken away and sectioned to better illustrate the details of the hinge structure of the ventilator;

Figure 6 is an enlarged detail of Figure 4 showing the adjustable mounting for the lower end of the hinge link;

Figure 7 is a vertical sectional view taken substantially on the plane of section line 7—7 of Figure 4;

Figure 8 is an enlarged fragmentary sectional view of a portion of Figure 3 illustrating the manner in which the geared operator is mounted in the jamb of the frame;

Figure 9 is a fragmentary front schematic view of the window assembly unit of Figure 3;

Figure 10 is an enlarged fragmentary vertical sectional view taken substantially on the plane of section line 10—10 of Figure 9;

Figure 11 is an exploded schematic view in perspective of a ventilator frame made pursuant to the present invention and illustrating the manner in which the ventilator frame elements are interconnected;

Figure 12 is a fragmentary perspective view of one of the jamb elements of the main frame made pursuant to this invention and illustrating the novel guide means for the slide bars and its manner of assembly in the jamb;

Figure 13 is a view similar to Figure 9 but showing a modified form of guide means;

Figure 14 is a fragmentary exploded perspective view illustrating a ventilator in the process of removal or installation; and

Figure 15 is a fragmental view of an upper corner of one of the ventilators with certain parts broken away to more fully illustrate the construction and assembly of the readily removable pintle or hinge supports provided by this invention.

With further reference to the drawings wherein like reference numerals are used throughout to indicate the same parts, there is disclosed a preferred embodiment of the present invention in which the numeral 10 designates a rectangular main frame. Main frame 10 is preferably composed of jamb elements 12 and 14, a header 16 and a sill 18 in the form of extrusions made from aluminum or other suitable metal, or plastic, or the like. The elements 12, 14, 16 and 18 are of general channel shaped configuration in cross-section with the inner and outer pairs of channel walls 19 (Figures 2, 12 and 13) cooperating with respective opposed pairs of rib or flange portions 20 and 22 and channel webs 21 to form inner and outer socket grooves extending longitudinally of the extrusion. These frame elements are miter cut at a 45° miter to length as required (Figure 9) to provide angled abutment joints at the four corners. While any suitable means may be employed to securely retain the several frame elements in proper rigid abutting relation, the present invention preferably employs outer

and inner angle plate joiners 23 and 24 (Figure 3A), the two legs of which have a driven fit in the respective socket grooves formed between the outer and inner channel walls of the abutting elements and their respective opposed rib formations 20 and 22. For a more detailed disclosure of these corner joints, reference may be had to copending application Serial Number 484,691, filed January 28, 1955 and entitled Structural Joints, now abandoned.

Suffice it to say that the joiners 23 and 24 have a tight or driven fit in the slots of the abutting frame elements and rigidly secure the elements together without the need for further corner connectors or laterally extending framing elements customarily employed to connect the jamb elements of awning type window structures.

One or more ventilators 26 form part of the invention. Each ventilator includes end frame bars 28 and 30, and upper and lower frame bars 32 and 34 all of double channel form in cross-section. The bars 28, 30, 32 and 34 are each formed with opposed longitudinal ribs defining opposed socket grooves 36 and 38 that extend throughout the lengths of the bars between the outwardly extending channel walls. The ends of the bars 28, 30, 32 and 34 are cut on a 45° miter to permit the ends of the bars 28 and 30 to tightly abut against the ends of the bars 32 and 34. Preferably these frame bars are formed as extrusions of aluminum or other suitable material miter cut to length as required. As will be clear from viewing the ends of the bars shown in Figure 11, the channel walls 39 are substantially longer than the opposite channel walls and are assembled to form the exterior face of the ventilator units so as to overlap the outermost exterior face of the main frame 10. (See Figures 1, 2, and 12.)

One flange or leg each of a plurality of angle joiners 40 are suitably driven into the ends of the socket grooves of the bars 32 and 34 and the exposed legs of the angle joiners are then suitably driven into the ends of the socket grooves of the bars 28 and 30, to securely interconnect the bars 28, 30, 32 and 34 and form a ventilator frame with inwardly facing channel openings of which are adapted to be glazed in well known manner. As will be clear from a consideration of Figures 1, 2 and 12, the continuous inner face formed by the opposed channel walls overlaps the innermost exterior face of the main frame to sealingly engage the flexible weatherstripping conventionally carried in the undercut groove therein (Figures 12 and 13).

Slide bar guides 42 comprising a cut off section of a continuous one piece extrusion (Figure 12) or a two piece assembly (Figure 13) made from mating cut off sections 43 and 45 of suitably formed pairs of extrusions are slidably adjustably engaged at spaced intervals in socket grooves 20 of the side members 12. The guides 42, extending transversely between the socket grooves 20, are formed with reduced end portions 44 that engage one of the socket grooves 20 and slots 46 in the other end portions of the guides 42 receive the ribs 48 of the other socket groove 20 as shown in Figure 12. Set screws 50 carried by the guides 42 and threaded into binding engagement against the back walls of the side members 12 and 14 force the end portions of the guides 42 to frictionally grip the socket groove walls. These guides 42 are formed with rectangular openings 52 for slidably receiving slide or actuating bars 54 whereby the slide bars will be guided during their longitudinal movements within the side members. Preferably guides 42 and slide bars 54 are assembled in the side frame elements before the frame elements are joined to their mating header and sill members since later assembly would be difficult. The two piece guides, however, permit ready removal of slide bars 54 should occasion demand and for this reason may be preferred by some users.

Pintle plates 56 are removably secured to the upper

corners of the ventilators 26 and support laterally outwardly extending pintle or hinge pins 60 that engage between the outer bifurcated ends of arms 62 fixed to the slide bars 54 by suitable screw fasteners 63 threaded into the slide bars. U-shaped holding dogs 64 pivotally carried by the pins 60 are adapted to coact with arms 62 to retain the pins 60 engaged with the arms 62. To this end dogs 64 are arcuately slotted as indicated at 67 to partially encircle locking pins 66 removably threaded into registering apertures in the arms 62 and having enlarged heads to frictionally clamp dogs 64 against the inner faces of arms 62.

While plates 56 may be secured in any suitable manner to end frame elements 28-30, they preferably take the form shown in Figure 15. As there shown plate 56 comprises a main base portion spanning socket grooves 36-38 of end frame elements 28-30 and a pintle carrying portion of reduced width extending outwardly beyond the opposed ends of grooves 36-38 and extending parallel to the plane of grooves 36-38 in outwardly spaced overlapping relation to corner joiner elements 40 employed to connect the respective end frame elements to top frame element 32. Suitable screws 57 respectively passing through the base portion of plate 56 in position to respectively thread into the main web of elements 28-30 and the respective corner joiners 40 secure plates 56 against movement with respect to frame elements 28-30 within the space between the opposed ribs.

The socket grooves 22 of the side members 12 and 14 slidably accommodate anchor plates 68 that support pivot pins 70 for the lower ends of hinge links or fulcrum arms 72. Clamp screws 74 pass through suitable apertures formed in the side members 12-14, extend through slots 76 in the plates 68 and thread into pressure strips or washers 78, which overlie plates 68 in the area of the space between grooves 22, to lock plates 68 in final adjusted position. This locking is effected by tightening screws 74 so as to draw the washers 78 against the plates 68 thereby causing the plates to bear against the main web of side members 12-14 and lock the plates 68 in adjusted position. In this manner the pivot pins 70 may be selectively raised or lowered for a purpose later to be described.

The other ends of hinge links 72 are connected to anchor plates 80 slidably and adjustably engaged in the socket grooves 34 and 36 of ventilator side members 28 and 30. The plates 80 fixedly support pins or trunnions 82 that extend laterally from side members 28-30 and into suitable apertures in the upper ends of the hinge links 72. Peripheral grooves are formed in the outer ends of pins 82 to accommodate resilient C-clips 84 that retain the links 72 removably pivoted to pins 82.

A laterally extending torque shaft 86 positioned in the sill 18 has its opposite ends fixedly connected to torque shaft arms 88 which are connected by pitmans 90 to the lower ends of the slide bars 54 for raising and lowering bars 54 and closing and opening ventilators 26 in unison. Rotational movement is imparted to shaft 86 by a novel operator mechanism carried by a sectional journal box or housing 92 suitably secured in the lower end of one of the side members 12 or 14. This housing, preferably formed from a novelly shaped extrusion, houses a gear segment 94 fixedly secured to shaft 86 and meshingly engaging a worm gear 96 rotatably supported in the housing. The rear end of worm gear 96 terminates in a cylindrical extension 98 protruding through the interior face of the selected side member which extension is held within the socketed end of removable operating crank handle 100 by a set screw 102.

While any suitable means may be employed to fixedly connect shaft 86 to arms 88 and gear segment 94, arms 88 and segment 94 are preferably provided with multi-sided openings that receive related portions of a multi-sided torque shaft 86 which passes freely through an enlarged annular opening in the housing 92 so that as the

gear segment 94 is rotated by worm gear 96, the torque shaft and its connected arms 88 will also be rotated to impart through pitmans 90 a vertical sliding movement to the slide bars for raising or lowering the ventilators.

Referring for the moment specifically to Figure 4, it will be noted that pivot pin 60 is disposed forwardly of the longitudinal axis of slide bar 54 whereas pivot pin 70 is disposed rearwardly of the longitudinal axis of slide bar 54. As a result of this relationship, the pivot pins 60, 10 70 and 82 define what is commonly known in the art as a balancing and locking triangle. Accordingly the ventilators 26 are properly balanced and pivotally connected to the operating mechanism to permit convenient opening of the ventilators and subsequent closing of the ventilators 15 against the side members.

The location of pivot pin 60 as illustrated also permits the ventilators 26 to be raised above the horizon or a plane perpendicular to the side members 12 and 14 without the upper edges of the ventilators 26 binding against 20 the side members 12 and 14. Thus it will be apparent that the ventilators themselves may be positioned to serve as deflectors for directing descending cool air into a room equipped with the novel window structure of this invention and to aid removal of hot air from the ceiling area.

25 It has heretofore been explained that slide plates 68 are vertically adjustable for the purpose of selectively raising or lowering the pivot pins 70. This adjustment is necessitated due to the fact that frequently a selected end of a selected ventilator may not fit tightly against one 30 of the side members because of incorrect installation of the frame 10 or extrusion tolerances varying in the various ventilator and frame forming members. Therefore, the simple and practical method thus utilized in the present invention for maintaining the pivot 70 in a vertically 35 adjusted position expedites the proper alignment of the ventilators to overcome this trouble if and when it arises.

Referring now to Figure 14, it will be seen that clamp screws 66 for securing pintle plates 56 to their respective 40 support arms 62 are readily accessible to a person standing in a room equipped with the window of this application. Consequently, removal of the ventilators can be 45 readily effected by loosening the opposite screws 66 to release the opposed holding dogs 64, then rotating the respective dogs on their pivot pins to free the dogs from 50 their clamp screws 66, and finally removing the resilient C-clips 84 from pivot pins 82 and bowing one or the other of the hinge links 72 outwardly to disassociate it from its associated hinge pin thereby freeing the window at one end so as to permit it to be tilted inwardly toward 55 the interior of the room and withdrawn from its other hinge link 72. It should be noted that this removal process assures a positive support for the ventilator right up to the time that positive action is taken to bow one of the hinge links to free the ventilator. As a consequence, 60 accidental disassociation of the ventilator in installing and removing it is adequately safeguarded.

It will further be apparent that the window unit of 65 this invention may be properly adjusted for operation at the factory so that installation of the unit on the job may be readily effected with the ventilators appropriately marked, removed and all linkage turned to a position within the confines of the main framing to guard against accidental damage. Removal of the crank handle 100 will assure that no one will inadvertently expose any 70 linkage for possible damage and removal of the ventilators will positively prevent use of the unit as a ladder or a scaffold board support.

To assure proper journaling and slidability of the 75 various parts all points where metal to metal contact between relatively movable parts occurs are provided with Teflon, nylon or similar self lubricating bushings or slide pads to prevent galling and corrosion of the parts due to electrolytic action. This feature is disclosed and claimed in my co-pending application Serial No. 618,358, entitled Awning Window and Parts Thereof.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description; and all changes which come within the meaning and range of equivalency of the claims are therefore intended to be embraced therein.

What is claimed and desired to be secured by United States Letters Patent is:

1. An awning or like window assembly comprising a main frame made up solely of opposed jamb and opposed header and sill members defining an unobstructed window opening; at least one glazed ventilator unit extending from one jamb member to the other jamb member to close at least a portion of the window opening defined by said rigid main frame; individually releasable hinge means hingedly mounting said glazed ventilator unit between said jamb members whereby said ventilator unit is readily removable for glazing or cleaning; an actuating means carried by said frame member in accessible relation to a person at the interior side of said window assembly for pivoting said ventilator unit around the axis of said hinge means between open and closed positions whereby said window may be removed to ventilate a room equipped with said window assembly and to expose said hinge means for releasing it to permit removal and replacement of said ventilator unit for assembly of said frame in a building wall and glazing or cleaning of said ventilator unit, said jamb members being of general channel shaped configuration with the channel grooves facing toward the exterior face of the frame and said actuating means comprising respective slide bars housed by the channel grooves of each jamb member, support brackets individual to each slide bar and adjustably secured to said respective jamb members to slidably support said respective slide bars, a hinge bracket secured to each of said slide bars and having an open sided pintle socket offset toward the exterior frame face and respective fulcrum arms having ends removably pivotally secured to said jamb members in opposed relation below each said hinge bracket in a vertical plane offset toward the interior frame face, said pintle socket being adapted to cooperatively pivotally receive the hinge pin of a ventilator unit mounted hinge means for supporting said ventilator for swinging movement around said pintle socket axis as a hinge axis and said free ends of said fulcrum arms being releasably pivotally connected to said ventilator unit at a point disposed below said pintle when said ventilator is closed.

2. An awning or like window assembly comprising a main frame made up solely of opposed jamb and opposed header and sill members defining an unobstructed window opening; at least one glazed ventilator unit extending from one jamb member to the other jamb member to close at least a portion of the window opening defined by said rigid main frame; individually releasable hinge means hingedly mounting said glazed ventilator unit between said jamb members whereby said ventilator unit is readily removable for glazing or cleaning; an actuating means carried by said frame member in accessible relation to a person at the interior side of said window assembly for pivoting said ventilator unit around the axis of said hinge means between open and closed positions whereby said window may be removed to ventilate a room equipped with said window assembly and to expose said hinge means for releasing it to permit removal and replacement of said ventilator unit for assembly of said frame in a building wall and glazing or cleaning of said ventilator unit, said jamb members being of general channel shaped configuration in cross-section with the channel grooves facing toward the exterior face of said frame and having inner opening defining walls

substantially shorter than the outer channel walls and each of said walls at its free end being formed with an inwardly and return bent, longitudinally directed flange element and with the base wall having a pair of longitudinally extending rib formations thereon disposed in opposed relation to the respective flange formations to cooperate therewith and form opposed socket grooves along the inner face of each side wall for respectively receiving inner and outer corner connecting brackets for rigidly joining said side frame members to said header member and said sill member.

3. The window assembly of claim 2 wherein said support brackets extend between said opposed socket grooves and have end formations extending into said grooves and clamp screws threaded through said brackets with their ends disposed to abut the jamb wall between said grooves and force said brackets bodily toward the respective groove defining flange elements and rib formations to frictionally lock said brackets at a selected point along said jamb.

4. The window assembly of claim 2 wherein the said individually releasable hinge means includes fulcrum arms removably, pivotally secured to said jamb members by securing screws carried by the base wall of said jamb, pintle plates slidably movable longitudinally of said jamb and having screw receiving slots therebetween and nut elements disposed in overlying relation to the slots in said pintle plates between said respective groove defining flange elements and rib formations so as to frictionally clamp said pintle plates between said jamb base walls and said nut elements.

5. An awning or like window assembly comprising a main frame made up solely of opposed jamb and opposed header and sill members defining an unobstructed window opening; at least one glazed ventilator unit extending from one jamb member to the other jamb member to close at least a portion of the window opening defined by said rigid main frame; individually releasable hinge means hingedly mounting said glazed ventilator unit between said jamb members whereby said ventilator unit is readily removable for glazing or cleaning; an actuating means carried by said frame member in accessible relation to a person at the interior side of said window assembly for pivoting said ventilator unit around the axis of said hinge means between open and closed positions whereby said window may be removed to ventilate a room equipped with said window assembly and to expose said hinge means for releasing it to permit removal and replacement of said ventilator unit for assembly of said frame in a building wall and glazing or cleaning of said ventilator unit, said glazed ventilator unit comprising transversely spaced end frame members and top and bottom frame members and the outer peripheral face of at least each end frame member being of channel shaped configuration in cross-section with the opposed channel walls having opposed rib-like, longitudinally extending formations adjacent their inner ends defining with the base wall opposed socket grooves and wherein said hinge means comprises a pintle plate having edge portions slidably received in said opposed socket grooves, a pintle carried by the central portion in transverse centered relation to said edge portions and a locking plate pivotally carried by said pintle and having an arcuate slot therein adapted to be moved into mating engagement with a part of said actuating means to removably secure said ventilator in operative relation to said main frame.

6. In an awning type window having a frame and a swinging ventilator; actuating mechanism comprising hinge links pivotally connecting the ventilator to the frame; vertically disposed slide bars slidably carried by the frame; means removably and pivotally connecting the ventilator to the slide bars; and operator means operatively connected to the slide bars for imparting sliding movement to the latter, said first named means including

rigid arms fixed to and projecting outwardly away from said slide bars and terminating at their outer ends in bifurcated end portions, pivot pins received in said bifurcated end portions for removably pivotally connecting said ventilator to said arms in offset relation from the longitudinal axes of said slide bars, plates fixed to said ventilator and supporting said pivot pins, and holding dogs pivotally supported on said pins and having portions thereof engageable with a part of said arms to retain said pivot pins operatively in said bifurcated end portions.

7. A window assembly comprising a frame including a pair of vertical side members, a header connected to the upper ends of said side members and a sill connected to the lower ends of said side members, said side members, said header and said sill each having a pair of opposed socket grooves extending throughout their lengths, each of said side, header and sill members having a web member extending transversely of the plane of the window opening and carrying along its opposite marginal edges parallel flanges and means spaced outwardly from the face of said web remote from said window opening and forming said pair of opposed socket grooves so as to be completely concealed from view from said window opening; an upper pair of angle joiners drive fitted in the adjacent ends of the opposed socket grooves of said side members and said header at each end of said header; a lower pair of angle joiners drive fitted in the adjacent ends of the opposed socket grooves of said side members and said sill at each end of said sill; respective slide bars carried by said side members for vertical sliding movement; a ventilator having its upper corners pivotally attached to said slide bars for swinging movement with respect thereto; anchor plates slidably adjustably positioned in the opposed socket grooves of said respective side members; link means individual to each slide bar having their lower ends respectively pivotally attached to said anchor plates and their upper ends respectively pivoted adjacent the upper corners of said ventilator.

8. In an awning window assembly a main frame comprising a pair of opposed jamb members, a header member and a sill member each of which comprises a channel member and includes a wall extending transversely of the plane of the window opening and carrying along its opposite marginal edges parallel flanges and means spaced from the face of said wall remote from the center of said frame and forming laterally opposed socket grooves intersecting each other at the mitered ends and opening on the side of said members remote from the center of said frame; corner joiner members in the form of angle irons having their respective legs drive fitted into the respective intersecting socket grooves at each corner to rigidly secure said header and sill to said opposed jambs in a manner to provide an unobstructed window opening; ventilator actuating means disposed in the channels of said jambs and including slide bar guides adjustably positioned in the socket grooves of said jambs; a plurality of ventilator units removably pivotally connected to said actuating means at opposed vertically spaced points; respective pairs of fulcrum arms individual to each ventilator unit each having one end removably connected to the opposite end of its respective ventilator unit; and anchor means respectively connecting each of the free fulcrum arm ends to said jambs whereby said plurality of ventilator units will be fixedly located longitudinally of said jambs for bodily in and out swinging movement in accordance with the operation of said actuating means to close or progressively open said window opening to control the ventilation through said unobstructed window and expose said removable connections for access to a person desiring to remove said ventilators for cleaning or glazing.

9. An awning window assembly according to claim 8 wherein said actuating means includes a torque bar extending transversely along the sill and fixedly connected adjacent its opposite ends to torque arms disposed within

the channel openings of said jambs, respective slide bars guided for longitudinal movement in said channel openings, pitman links connecting said respective torque arms to said respective slide bars and a geared operating mechanism mounted in the channel opening of one of said jambs and having a worm gear non-rotatably secured to the adjacent torque bar end and worm pinion and shaft having a free shaft end extending through the web of said one jamb and removably mounting an operating crank.

10. In an awning window assembly, a main frame comprising generally channel-shaped laterally spaced jambs, a header and a sill each having mitered ends disposed in respective abutting relation and longitudinally extending, laterally opposed socket grooves intersecting each other at the mitered ends; corner joiner members in the form of angle irons having their respective legs drive fitted into the respective intersecting socket grooves at each corner to rigidly secure said header and sill to the respective opposed ends of said jambs in a manner to provide an unobstructed window opening; ventilator actuating means disposed in the channels of said jambs; a plurality of ventilator units removably pivotally connected at laterally opposed corners to said actuating means at laterally opposed vertically spaced points; respective pairs of fulcrum arms individual to each ventilator unit and each having one end removably pivotally connected to the opposite lateral ends of its respective ventilator unit; anchor means respectively pivotally connecting each of the other fulcrum arm ends to said jambs whereby said plurality of ventilator units will be fixedly located longitudinally of said jambs for bodily in and out swinging movement in accordance with the operation of said actuating means to close or progressively open said window opening to control the ventilation through said otherwise unobstructed window opening and expose said removable pivotal connections for access to a person desiring to bodily remove said ventilator units for cleaning or glazing, said actuating means including a torque bar extending transversely along the sill channel opening and fixedly connected adjacent its opposite ends to respective torque arms disposed in closed position of said ventilator units within the channel openings of said jambs, respective slide bars guided for longitudinal movement in said jamb channel openings, pitman links connecting the free ends of said respective torque arms to said respective slide bars, and a geared operating mechanism mounted in the channel opening of one of said jambs at the adjacent end of said torque bar and having a worm gear non-rotatably secured to said adjacent torque bar end, and a worm pinion and shaft having a free shaft end extending through the interior face web of said one jamb and removably mounting an operating crank; the guides of said slide bars comprise two or more sectional lengths of an extrusion having a laterally extending mounting section of minimum thickness adapted for sliding connection along the inner face of one of the opposed walls of said jambs, a thickened guide section apertured at right angles to the opposite cut off ends of said sectional lengths to form a slide bar guide opening and screw means acting between a portion of said mounting section and said inner wall face to secure said slide bar guide in place along said jamb.

11. An awning window assembly according to claim 10 wherein said inner jamb wall is provided with integral, overhanging, laterally opposed, flange-like formations co-operating with said inner wall surface to form opposed socket grooves, the opposite edges of said mounting section are formed for mating sliding engagement in said opposed socket grooves and said screw means comprises a set screw threaded through said mounting section into abutting engagement with said inner wall surface to frictionally lock said slide bar guide at a selected point along said jamb.

12. In an awning window assembly, a main frame com-

prising generally channel-shaped laterally spaced jambs, a header and a sill each having mitered ends disposed in respective abutting relation and longitudinally extending, laterally opposed socket grooves intersecting each other at the mitered ends; corner joiner members in the form of angle irons having their respective legs drive fitted into the respective intersecting socket grooves at each corner to rigidly secure said header and sill to the respective opposed ends of said jambs in a manner to provide an unobstructed window opening; ventilator actuating means disposed in the channels of said jambs; a plurality of ventilator units removably pivotally connected at laterally opposed corners to said actuating means at laterally opposed vertically spaced points; respective pairs of fulcrum arms individual to each ventilator unit and each having one end removably pivotally connected to the opposite lateral ends of its respective ventilator unit; anchor means respectively pivotally connecting each of the other fulcrum arm ends to said jambs whereby said plurality of ventilator units will be fixedly located longitudinally of said jambs for bodily in and out swinging movement in accordance with the operation of said actuating means to close or progressively open said window opening to control the ventilation through said otherwise unobstructed window opening and expose said removable pivotal connections for access to a person desiring to bodily remove said ventilator units for cleaning or glazing; said ventilator units comprising opposed, end frame members and top and bottom frame members having mitered ends disposed in abutting relation and longitudinally extending, laterally opposed socket grooves formed along the peripherally outwardly exposed faces and intersecting each other at the mitered ends, corner joiner members in the form of angle irons having their respective legs drive fitted into the respective intersecting socket grooves at each corner to rigidly secure said top and bottom frame members to said end frame members; and said removable pivotal connection to said actuating means comprises a pintle plate associated with each end frame member and having a supporting section slidably disposed in said opposed socket grooves of said ventilator end frame members, a pintle mounting section extending outwardly from said supporting section between said opposed socket grooves and lying in a plane parallel to the plane of said supporting section, a pintle protruding from said pintle mounting section and having an enlarged head at its outer free end, a locking plate pivotally carried by said pintle adjacent said pintle mounting section and having an arcuate groove therein, set screws for frictionally locking said pintle plate in position along said end frame members and a clamp screw having a shank threaded into said actuating means in position to cooperate with said arcuate groove and a head adapted to clampingly overlap the locking plate at the sides of said arcuate groove to frictionally secure said locking plate to said actuating means with said pintle in journaling relation thereto.

13. In an awning window assembly, a main frame comprising generally channel-shaped laterally spaced jambs, a header and a sill each having mitered ends disposed in respective abutting relation and longitudinally extending, laterally opposed socket grooves intersecting each other at the mitered ends; corner joiner members in the form of angle irons having their respective legs drive fitted into the respective intersecting socket grooves at each corner to rigidly secure said header and sill to the respective opposed ends of said jambs in a manner to provide an unobstructed window opening; ventilator actuating means disposed in the channels of said jambs; a plurality of ventilator units removably pivotally con-

nected at laterally opposed corners to said actuating means at laterally opposed vertically spaced points; respective pairs of fulcrum arms individual to each ventilator unit and each having one end removably pivotally connected to the opposite lateral ends of its respective ventilator unit; anchor means respectively pivotally connecting each of the other fulcrum arm ends to said jambs whereby said plurality of ventilator units will be fixedly located longitudinally of said jambs for bodily in and out swinging movement in accordance with the operation of said actuating means to close or progressively open said window opening to control the ventilation through said otherwise unobstructed window opening and expose said removable pivotal connections for access to a person desiring to bodily remove said ventilator units for cleaning or glazing; said removable connection between said fulcrum arms and said ventilator units comprising a pintle plate having a pintle protruding from one face thereof, opposed socket grooves formed along the lateral edges of said ventilator end frame members to slidably receive the edges of said pintle plate, set screw means threaded through said plate for frictionally locking said pintle plate in adjusted position along said opposed socket grooves, an annular groove in said pintle adjacent its free end and a C-shaped snap ring for removable association with said annular groove to lock said fulcrum arm in assembled relation on said pintle.

14. In an awning type window having a frame, a swinging ventilator, hinge links removably pivotally connected to the ventilator, hinge link connection means connecting said hinge links to the frame side members comprising a pair of opposed vertical socket grooves in the frame side members, anchor plates slidably adjustably mounted in said grooves, and pivot pintles connecting said hinge links to said anchor plates, slide bars slidably carried by the frame and operator means operatively connected to the slide bars for imparting sliding movement to the latter; means removably and pivotally connecting said slide bars to the ventilator comprising opposed frame supported pivot pins, and a pair of coacting hinge components at each end of the ventilator comprising an open sided pivot pin receiving socket protruding beyond the inner face of the ventilator and separable from a respective pivot pin by movement of the hinged end of the ventilator outwardly from the frame and a pivoted lock dog for closing said open side of said pin receiving socket and preventing such separation of said hinge components and pivot pin.

15. The combination of claim 14 together with pressure strips carried by said side members and relatively adjustably bearing against said anchor plates to retain said plates adjusted in said grooves.
